UNITED STATES PATENT OFFICE

BENJAMIN F. HOBSON, OF MONTICELLO, ARKANSAS, ASSIGNOR OF ONE-HALF TO T. C. DEAL, OF MONTICELLO, ARKANSAS

PICK MECHANISM FOR LOOMS

Application filed December 22, 1928. Serial No. 327,892.

This invention relates to looms and particularly to the means whereby the shuttles are projected across the lay beam of the loom and to means whereby the lay beam is vibrated toward and from the shed.

The general object of the invention is to provide an improved picker stick motion, as it may be called, which does away with the ordinary picker sticks and the actuating cams therefor but which includes a spring projected striker at each end of the lay beam, and means intermittently operated for retracting the striker, the striker, being projected by a spring.

A further object is to mount the lay beam upon guides so that it may reciprocate back and forth toward the shed and provide means for reciprocating the lay beam and actuating the shuttle strikers or picks.

A further object is to provide a mechanism of this character which is more positive in its action, in which the pick mechanism is enclosed and which may be mounted upon the ordinary loom frame.

Other objects will appear in the course of the following description.

My invention is illustrated in the accompanying drawings, wherein:

Figure 1 is a top plan view of a portion of a loom with my pick mechanism applied thereto with the lay beam forward;

Figure 2 is a like view to Figure 1 but showing the lay beam shifted rearward;

Figure 3 is a section on the line 3—3 of Figure 1;

Figure 4 is an enlarged longitudinal sectional view through one end of the lay beam showing the pick mechanism;

Figure 5 is a fragmentary view on the same section line as Figure 4 but showing the action of the cam on the pick.

Referring to the drawings, 10 designates the loom frame of any suitable or usual character. This frame is provided with the longitudinally extending guides 11 formed as rails disposed in a horizontal plane. The lay beam 12 is of any suitable or usual form and carries upon it vertically disposed members 13, the lower ends of which are formed to provide the slides 14 which slidably engage the

rails 11. The members 13 which support the lay beam have such an angle with relation to the slides that the lay beam is always supported at the proper angle with relation to the shed. The members 13 extend upward and support the reed rail 15 carrying the reed 16. The members 13 are outwardly flanged at their lower ends as at 17.

Disposed rearward of the lay beam is the transverse shaft 18 formed with the cranks 19. Connecting these cranks with the members 13 and the lay beam are the connecting rods 30, these connecting rods having bearings at their forward ends engaging with transverse pins 31 extending through the flanges 17. By this means rotary motion given to the crank shaft will cause reciprocation of the lay beam. Any suitable train of gear may be used for driving the crank shaft.

As illustrated, the members 13 are mounted upon the lay beam by inserting member 13 between the ears 20 and pinning or screwing the member 13 to the lay beam. The reed is mounted upon the upper ends of these members 13 by means of the screw 21.

Disposed at the ends of the lay beam are the picks whereby the shuttle is thrown across the face of the lay beam. Each of these picks consists of an angular member 22, one end of which passes through a support 23 mounted upon the lay beam. This end is formed with a cup 24 engageable with the extremity of the shuttle. The lower end of the angular member 22 is horizontally extended beneath the lay beam in bearings formed in the members 23 and is engaged by a spring 25 which urges the pick inward or toward the shuttle. The member 22 projects out beyond the spring 25 and toward a horizontally extending shaft 26. There are two of these shafts, of course, mounted on each side frame 10. Each of these shafts at its end is geared by beveled gears to the crank shaft 18 and may be driven therefrom in any suitable manner. Mounted upon each shaft 26 is a cam 27 which as it rotates with the shaft strikes against a member 28 carried upon the lower extremity of the member 22.

This head 28 is so formed as to receive the

impact of the cam and as the cam rotates the pick will be forced out against the action of the spring, thus retracting the pick from the shuttle. As soon as the cam has passed the head 28, the cam suddenly releases the pick which is projected toward the end of the lay beam violently under the action of the spring 25, thus projecting the shuttle from one shuttle box on one end of the lay beam to the 10 opposite end of the box on the other end of the lay beam. The shuttle boxes are designated 29 and are so formed as to enclose the spring 25, arch over the end of the pick, and protect the vertical portion of the member 22. 15 The ends of the lay beam may be cut away if desired to accommodate the picks. It will be noted that the slides and rails 14 and 11 are disposed at such an angle that the reed rail will always have the proper angle of the 20 shed when in operation.

This construction is particularly adapted to be used in connection with a Draper loom or a Stafford loom though I do not wish to be limited to this application of my invention. The construction which I have devised sets up much less vibration, is less expensive to operate, requires less material to construct, gives more space around the machine, is safer to operate and exerts less strain and friction 25 on the shed than other mechanisms for this purpose known to me. The reed rail operates at the angle of the shed which decreases to some degree the possibility of the shuttle hanging and breaking the thread, thus costing 30 much less in the upkeep.

While I have illustrated certain construction which I believe to be particularly effective for this purpose, I do not wish to be limited thereto as it is obvious that this might 40 be modified in many ways without departing from the spirit of the claims.

I claim:

1. In a loom, a supporting frame, a lay beam, spring projected picks mounted upon 45 the ends of the lay beam, and power operated cams elongated in the direction of movement of the lay beam and at right angles to the direction of movement of the picks engaging said picks and intermittently forcing 50 them outward against the action of said spring and then releasing the picks to permit their projection by the spring.

2. In a loom a supporting frame, a lay beam mounted for movement in a horizontal 55 plane toward and from the shed, picks mounted upon the lay beam at each end thereof, each pick having a portion movable horizontally beneath the lay beam, a spring urging 60 each pick inward, a horizontally disposed power driven shaft associated with each pick and approximately parallel to the path of 65 movement of the lay beam, and a cam elongated in a direction parallel to the direction of movement of the lay beam and at right 70 angles to the direction of movement of the

70 picks and carried upon the shaft for bodily rotation therearound and as the shaft rotates intermittently engaging said pick to force it outward against the action of said spring and then release it.

3. In a loom a supporting frame, a lay beam mounted for movement in a horizontal plane toward and from the shed, picks mounted upon the lay beam at each end thereof, each pick having a portion extending horizontally beneath the lay beam, a spring urging 75 each pick inward, a horizontally disposed power driven shaft associated with each pick and extending parallel to the direction of motion of the lay beam, and a cam elongated in the direction of movement of the lay beam and carried upon each shaft and rotatable bodily therearound and as the shaft rotates intermittently engaging said pick to force it outward against the action of said spring and then release it, each pick at its inner end and adjacent the shaft being provided with a 80 head with which the cam engages.

4. In a loom, a supporting frame, a lay beam, spring projected picks mounted upon 85 the ends of the lay beam, shafts mounted upon the frame and extending parallel to the direction of motion of the lay beam, cams mounted upon said shafts, each cam being elongated in the direction of motion of the 90 lay beam and at right angles to the direction of motion of the picks, each cam being carried upon the shafts for bodily rotation therearound whereby each cam will intermittently engage against the corresponding pick to 95 force each pick outward against the action of said spring and then release the pick to permit its projection by the spring, each cam being longitudinally adjustable upon its shaft.

5. In a loom, a supporting frame, a lay beam, spring projected picks mounted upon 100 the ends of the lay beam, shafts mounted upon the frame and extending parallel to the direction of motion of the lay beam, cams mounted upon said shafts, each cam being elongated in the direction of motion of the lay beam and at right angles to the direction of motion of the picks, each cam being carried upon the shafts for bodily rotation therearound whereby each cam will intermittently engage against the corresponding pick to 105 force each pick outward against the action of said spring and then release the pick to permit its projection by the spring, each cam being longitudinally adjustable upon its shaft.

6. In a loom, a supporting frame, a lay beam, spring projected picks mounted upon 110 the ends of the lay beam, shafts mounted upon the frame and extending parallel to the direction of motion of the lay beam, cams mounted upon said shafts, each cam being elongated in the direction of motion of the lay beam and at right angles to the direction of motion of the picks, each cam being carried upon the shafts for bodily rotation therearound whereby each cam will intermittently engage against the corresponding pick to 115 force each pick outward against the action of said spring and then release the pick to permit its projection by the spring, each cam being rotatably adjustable upon its shaft.

120

125

130

whereby each cam will intermittently engage against the corresponding pick to force each pick outward against the action of said spring and then release the pick to permit its projection by the spring, each cam being rotatably and longitudinally adjustable upon its shaft.

In testimony whereof I hereunto affix my signature.

BENJ. F. HOBSON.
